FENDER GUIDE ROD

Gerald E. Stahl, Rye, N. Y., assignor to Casco Products Corporation, Bridgeport, Conn., a corporation of Connecticut

Application August 14, 1956, Serial No. 42,605

Term of patent 3½ years

(Cl. D14—6)

Fig. 1

Fig. 2

Fig. 3

Fig. 4

Figure 1 is a guide elevation of a fender guide rod showing my new design.

Fig. 2 is a front elevation of the fender guide rod shown in Fig. 1.

Fig. 3 is a plan view of the fender guide rod shown in Fig. 1.

Fig. 4 is a transverse section taken on the line 4—4 of Fig. 1.

Fig. 5 is a perspective view taken from the rear left of the fender guide rod.

I claim:

The ornamental design for a fender guide rod, as shown.
